TELEPHONE SYSTEM

Herbert M. Friendly, deceased, late of Chicago, Ill., by Milton S. Friendly and Central Trust Company of Illinois (now by change of name Central Republic Trust Company), Chicago, Ill., co-executors, assignors to Milton S. Friendly, Chicago, Ill., Oscar N. Friendly, Salt Lake City, Utah, and Central Republic Trust Company, Chicago, Ill., a corporation of Illinois, trustees under the will of Herbert M. Friendly, deceased

Application November 14, 1931, Serial No. 575,135

27 Claims. (Cl. 179—7.1)

The present invention relates in general to automatic telephone systems, and more particularly to measured service automatic telephone systems.

5 One of the objects of the present invention is to provide means under the control of the called subscriber whereby he can reverse the metering charge from the calling subscriber's line to his own.

10 Another object is to provide mechanism by which the called subscriber may make this reversal at his option at any time during the conversation with the calling subscriber.

15 Another object is to provide a method of making a charge to the line of the called subscriber at his option in accordance with the length of the conversation.

20 Another object is to vary this time charge in accordance with the telephone traffic in the exchange.

25 A further object is to provide mechanism for rendering it impossible to reverse the charge with a restricted class of called subscribers.

30 A further object is to provide means for informing the subscribers when talking the amount of charge being made.

35 A still further object is to inform the subscribers whether the charge is being made against the calling or called party.

40 There are other objects of the invention, which, together with the foregoing, will be described in the detailed specification that is to follow, taken in conjunction with the accompanying drawings and forming a part thereof.

45 The invention has been illustrated in an automatic telephone system of the so-called Strowger type employing first selectors and connectors. Obviously, a greater number of selectors may be employed if necessary or desirable in accordance with well known principles.

50 In practicing the invention a metering device is provided for each line which it is desired to charge. A timing switch is associated with each first selector and with each connector in order to bring about the timing of the conversation. A push button is provided at each subscriber's telephone by which the called subscriber may reverse the charge.

55 Briefly, the operation of the invention proceeds in the following manner:

The connection between the calling and the called subscriber is established in the usual manner through the calling subscriber's line switch, an idle first selector and an idle connector.

55 When the subscribers are connected the timing

switch individual to the first selector is operated periodically to actuate the meter associated with the calling subscriber's line. In the event the called subscriber is one of those subscribers who may reverse the charges he presses the push button at this telephone, which brings about the cessation of the operation of the timing switch to the first selector and the initiation of the operation of the timing switch individual to the connector. The operation of the timing switch individual to the connector causes the meter associated with the called subscriber's line to be actuated periodically. Audible signals are applied to the line at short intervals before the charge is made, the tone being of one pitch to inform the called subscriber if the charge is being made against him and of another pitch to inform the calling subscriber if the charge is being made against him.

55 Referring now to the drawings comprising Figs. 1 to 3 inclusive, the invention has been illustrated in connection with a simple step by step type of automatic telephone system wherein the apparatus and circuits are shown by means of the usual conventional diagrams.

60 In Fig. 1 in the upper left hand corner of the sheet a calling subscriber's telephone is illustrated, designated with the reference character T. The telephone comprises the usual transmitter, receiver, switch hook and ringer. In addition, the telephone is provided with a push button 102 whose contacts normally short circuit a resistor included in the line circuit. Reference character RS designates the usual type of rotary line switch individual to the line of the subscriber at sub-station T. The line switch is provided with the usual line relay 109, switching relay 108 and motor magnet 114. The motor magnet 114 is operated to advance the switch wipers 110 to 113, inclusive, step by step over 65 associated bank contacts such as 121 to 124, inclusive, in search of an idle trunk. A metering device 107 of any usual or well known type is associated with each line switch. The rotary switches RS have access to trunk lines extending to first selectors such as the first selector S.

70 The selector S is generally of the usual and well known Powell type, having controlling relays 125 to 132, inclusive, and being provided with the usual vertical magnet 133, rotary magnet 134, and release magnet 135. The selector S has access to 10 groups of trunk lines terminating in 10 groups of bank contacts, such as the bank contacts 185 to 187, inclusive, accessible to switch wipers 136 to 138, inclusive. A rotary timing

switch RS-1, which may be of the same general mechanical construction as the rotary switch RS, is associated with each first selector such as S. The rotary switch RS-1 has access to bank contacts which are connected to metering and tone machine mechanism M. The metering and tone machine mechanism M is common to all the metering switches, such as RS-1, associated with the first selector S. This metering equipment 10 consists essentially of two motor driven shafts 174 and 181, upon which are mounted commutating segments 172 and 173 and 175 to 178, respectively. The commutating segments 172, 173, 177 and 178 are connected to the battery, while the commutating segments 175 and 176 go to tone machines and may generate audible signals of different pitch.

The trunk lines accessible to the first selectors S-1 extend to connectors C of the usual step by step type. The connector C is provided with control relays 200 to 210, inclusive, and the usual vertical magnet 212, rotary magnet 213, and release magnet 211. The connectors such as C are divided into 10 groups, each group having access to 100 subscriber's lines. Thus the connector C has access through the wipers 216 to 219, inclusive, and bank contacts such as 292 to 295, inclusive, to the lines of 100 subscribers. A timing switch RS-2 is individual to each connector. This switch may be of the same general mechanical construction as the switch RS previously described, having a motor magnet 264 for advancing the switch wipers 273 to 276, inclusive, about its associated bank contacts. The bank contacts of the timing switch are connected to common metering equipment M-2. The metering equipment M-2 consists essentially of two motor driven shafts 288 and 289, which are provided with the commutating segments 282, 283, 284 and 287 and 285 and 286, respectively. The commutating segments 284, 287, 285 and 286 are connected to the battery, while the commutating segments 282 and 283 are connected to tone machines capable of generating signals of different pitch. In addition, a common metering device M-1, which consists of a clock driven wiper 261 adapted to engage circular contacts twenty-four in number. For each hour of the day, the wiper 261 will be in engagement with a certain particular contact.

As before mentioned, the connector C has access to called telephone lines of 100 called subscribers, such as the subscribers located at stations T-1 to T-3, inclusive. Each of the called subscriber's lines is provided with rotary line switches such as RS-3 of identically the same construction as the rotary switch RS previously described. The telephone sub-station circuits of the called subscribers such as T-1 are of identically the same construction as the telephone sub-station T previously described, being provided with the usual transmitter, receiver, switch hook and ringer, and, in addition, push button 336 and resistor 335. A slightly modified form of sub-station circuit is shown at T-2, wherein the push button 337 is employed to ground one side of the line. The circuit of the telephone sub-station T-3 is of the usual type, not being provided with a push button. This is to illustrate the line of a called subscriber who has free service. The line of the sub-station T-3, in addition to terminating in the contacts of the connector C and other connectors of the same group, terminates in the rotary line switch RS-4. In addition relays, such as 317 to 319, are provided in association

with this line for the purpose of preventing the telephone subscriber at station T-3 from altering the metering charge of the calling subscriber when in connection with his line in any manner.

While the timing switches RS-1 and RS-2 associated with the first selector S and connector C, respectively, have been illustrated as individual to these switches, it will be understood that they may be made common by the use of finder switches or in any other suitable or well known manner.

Having briefly described the apparatus and circuits shown in the drawings, their detailed operation will now be described. For this purpose it will be assumed that the subscriber at sub-station T desires to call the subscriber at sub-station T-1. In order to accomplish this result the subscriber at sub-station T will remove his receiver from the switch hook, thereby completing a circuit which extends from ground by way of back contact and armature 117, line conductor 101, contacts of push button 102, switch hook contacts, receiver and transmitter in series, line conductor 100, armature 116 and its back contact, winding of line relay 109, and thence to battery. The slow 20 acting line relay 109 is energized over this circuit and serves to complete a circuit which extends from ground by way of armature 120 and its front contact, switching relay 108, back contact and armature of motor magnet 114, and then 25 through the winding of this magnet to battery, and at armature 119 and its front contact serves to connect the test wiper 111 to the above circuit at a point midway between the switching relay 108 and motor magnet 114. In the event that the 30 switch wipers 110 to 113, inclusive, are in engagement with a busy trunk line, ground will be connected to the bank contact associated with the test wiper 111, and the motor magnet 114 will be operated to advance the switch wipers 110 to 40 113, inclusive, until they are in engagement with the bank contacts associated with an idle trunk line. At this time there will be a circuit completed for the switching relay 108 in series with the motor magnet 114. The switching relay 108 45 upon operating connects the meter 107 to the metering wiper 110 at armature 115 and its front contact, opens the test circuit of the motor magnet 114 at armature 118 and at the front contact of this armature prepares a holding circuit 50 for the switching relay 108. At armatures 116 and 117 the operation of the switching relay 108 serves to open the circuit of the slow acting line relay 109 and to extend the talking conductors 100 and 101 to the wipers 112 and 113. It will be assumed that the trunk selected by the operation of the line switch is the trunk line terminating in the bank contacts 121 to 124, inclusive. Consequently, upon the extension of the talking conductors 100 and 101 as described there will be a circuit completed 55 extending from ground through the lower winding of the line relay 129, of the selector S, back contact and armature 148, bank contact 124, thence through the calling subscriber's telephone, bank contact 123, through the lower winding of 60 the electropolarized relay 127, armature 147 and its back contact, and thence through the upper winding of the line relay 129 to battery. The line relay 129 is energized over this circuit and upon operating opens a point in the circuit of the 65 release magnet 135 at armature 150 and its back contact, and at the front contact of this armature completes a circuit for the slow acting relay 130. The slow acting relay 130 upon operating 70 disconnects ground from certain bank contacts 75

in the timing switch RS—1 at armature 151 and its back contact, at the front contact of this armature connects ground to the holding or release trunk conductor, and at armature 152 and its front contact prepares a circuit for the vertical magnet 133. The connection of ground to the release trunk conductor serves to establish a holding circuit extending back to the switching relay 108 of the rotary switch RS and the motor magnet 114 in series, in order to maintain the switching relay 108 energized after the de-energization of the slow acting line relay 109. The application of ground to the release trunk also completes the circuit for the polarizing winding of the electropolarized relay 127.

When the calling subscriber at sub-station T operates his calling device CD in accordance with the first digit of the called subscriber's number a series of interruptions are produced in the circuit of the line relay 129 which retracts its armature a number of times corresponding to the number of interruptions. At each retraction of its armature 153 there is a circuit completed which extends from ground by way of armature 150 and its back contact, back contact and armature 149, armature 152 and its front contact, winding of slow acting relay 131, and vertical magnet 133 to battery. The vertical magnet is operated to raise the switch wipers 136 to 138, inclusive, opposite the proper level of the bank contacts. At the first off normal step of the switch the off normal springs 156 and 157 are shifted to prepare a circuit for the rotary and release magnets. The slow acting relay 131 is energized to open a point in the circuit of the rotary magnet 134 at armature 153, and to complete a circuit which extends from ground by way of armature 151 and its front contact, armature 153 and its front contact, armature 195 and its back contact, working contact of off normal spring 156 and said spring and interrupter relay 132 to battery. The interrupter relay 132 is energized over this circuit to establish a locking circuit for itself at armature 154 and to prepare the circuit for the rotary magnet 134 at armature 155.

A short interval after the calling device has returned to normal position the relay 131 is de-energized to complete a circuit for the rotary magnet 134 over a path that extends from ground by way of armature 151 and its front contact, armature 153 and its back contact, armature 155 and its front contact, and rotary magnet 134 to battery. The rotary magnet 134 is energized over the above circuit and operates to advance the switch wipers 136 to 138 inclusive, one step into engagement with the first set of bank contacts on the level selected. A further result of the operation of the rotary magnet 134 is that at armature 195 the circuit of the interrupter relay 132 is opened and it de-energizes. The de-energization of the interrupter relay 132 opens a point in the circuit of the rotary magnet at armature 155 and at armature 154 opens a point in its locking circuit. A test circuit is now established, which extends from the test wiper 136 by way of armature 146 and its back contact, armature 195 and its back contact, working contact of off-normal spring 156, and said spring and relay 132 to battery. If the trunk line with which the switch wipers 136 to 138 inclusive, are in engagement is busy, there will be a ground potential upon the bank contact engaged by the switch wiper 136 and the relay 132 will be energized over the above circuit to establish a locking circuit for itself at armature 154 and to complete a circuit for the rotary magnet at armature 155. The rotary magnet 134 upon operating opens the circuit of the interrupter relay 132, which is de-energized to interrupt the circuit of the rotary magnet. The alternate operation of the interrupter relay 132 and the rotary magnet 134 continues until the switch wipers 136 to 138 inclusive, are advanced into engagement with the bank contacts associated with an idle trunk line, which it will be assumed are the bank contacts 155 to 167, inclusive. When the switch wipers are brought into engagement with this set of bank contacts there will be no ground potential upon the bank contact 195 and no circuit will be completed for the interrupter relay 132. The circuit is now established which extends from ground by way of armature 151 and its front contact, winding of switching relay 128, armature 195 and its back contact, working contact of off-normal spring 156 and said spring and interrupter relay 132 to battery. On account of the high resistance of the relay 128, the interrupter relay 132 is not operated over this circuit. The switching relay 128 upon operating opens the point in the circuit of the release magnet at armature 149, opens a point in the testing circuit at armature 146, and at armatures 147 and 148 disconnects the talking circuit extending to the calling telephone from the windings of the line relay 129 and at the front contact of these armatures extends the calling line through the wipers 137 and 138, bank contacts 185 and 187, trunk conductors 197 and 198, through normally closed springs controlled by armatures 227 and 228 on relay 203 of the connector C, and thence to the upper and lower windings of the line relay 204 of the connector. The line relay 204 is energized over a circuit, including the calling line, and upon operating opens a point in the circuit of the release magnet at armature 231 at its back contact and at armature 231 and its front contact completes a circuit for the slow acting relay 205. The slow acting relay 205 upon operating opens a further point in the circuit of the release magnet at armature 233 and its back contact prepares a circuit for the vertical magnet at the front contact of this armature, disconnects ground from certain bank contacts in the timing switch or at armature 232 at its back contact, and at the front contact of this armature prepares a locking circuit for certain other relays. The operation of the relay 205 also connects ground to the release trunk conductor 166, whereby a locking circuit is established extending by way of this conductor, bank contact 185, test wiper 136, armature 146 and its front contact, relay 128, armature 195 and its back contact, working contact of off-normal spring 156, and said spring and relay 132 to battery.

This holding circuit is established prior to the de-energization of the slow acting relay 130, which occurs a short interval of time after the de-energization of the line relay 129 following the operation of the switching relay 128 previously described.

When the calling subscriber at sub-station T operates his calling device CD in accordance with the next digit of the called subscriber's number, there will be a series of interruptions produced in the circuit of the line relay 204 of the connector C and this relay will be de-energized a plurality of times. At each de-energization of the line relay 204 there is a circuit established, which extends from ground by way of armature 231 and its back contact, armature 233 and its

front contact, resting contact of off-normal spring 258, relay 206 and vertical magnet 212 to battery. The vertical magnet 212 is operated to raise the switch wipers 214 to 217 inclusive, 5 opposite the level of bank contacts corresponding to the digit of the called subscriber's number that has been dialed. The slow acting relay 206 is energized in series with the vertical magnet 212 and serves to prepare a new circuit for the 10 vertical magnet 212. At the first off-normal step of the switch the circuit of the vertical magnet is changed and may be traced over a path extending from ground by way of armature 231 and its back contact, armature 233 and its front contact, off-normal contacts 215, armature 234 and its front contact, relay 206 and vertical magnet 212 to battery.

A short interval of time after the calling subscriber's calling device restores to normal, the 20 slow acting relay 206 is de-energized to open a point in the circuit of the vertical magnet 212 and to prepare a circuit for the rotary magnet 213.

When the calling subscriber operates his calling device in accordance with the last digit of the called subscriber's number, there will be another series of interruptions produced in the line circuit, which includes the line relay 204 and this relay will be de-energized a corresponding number of times. At each de-energization of the line 25 relay 204 there is a circuit completed, which extends from ground by way of armature 231 and its back contact, armature 233 and its front contact, off-normal springs 215, armature 234 and its back contact, back contact and armature 241, back contact and armature 254, and rotary magnet 213 to battery. A branch of this circuit extends through the slow acting relay 209 to battery. The rotary magnet 213 is operated a plurality of times to advance the switch wipers 214 to 217, inclusive, into engagement with the bank contacts associated with the line of the subscriber at sub-station T-1, which it will be assumed are the bank contacts 292, 296, 294 and 298, respectively. The slow acting relay 209 is energized in parallel with the rotary magnet 213 and operates at armature 243 to prepare a circuit for the busy test relay 208 and to prepare an alternative circuit for itself and the rotary magnet 50 at armature 244 and its front contact, exclusive of the armature 241. This result is for the purpose of maintaining the circuit of the rotary magnet, irrespective of the energization of the busy test relay 208 in the switch wipers 216 55 to 219 passing over busy lines. This result is brought about by the test wiper 217 encountering a ground potential upon bank contacts it rotates over, and bringing about the operation of the relay 208.

It will first be assumed that the line of the called subscriber at sub-station T-1 is busy. In this instance there will be a ground potential applied to the bank contact 296, and when the test wiper 217 is brought into engagement with this 60 bank contact a circuit will be established extending to the busy test relay 208. The busy test relay 208 upon operating prepares a locking circuit for itself at armature 240, opens a point in the rotary magnet circuit at armature 241, 65 and at armature 242 applies the busy tone to a conductor extending to the calling telephone. A short interval after the cessation of the last series of impulses the slow acting relay 209 is de-energized to open another point in the rotary 70 magnet circuit at armature 244 and to establish 75

the locking circuit of the relay 208 at the normally closed springs controlled by armature 243. This locking circuit may be traced from ground by way of front contact and armature 214, armature 240 and its front contact, normally closed 5 springs controlled by armature 243, armature 252 and its back contact and relay 208 to battery.

Upon the calling subscriber getting the busy signal he will place his receiver upon the switch hook, thereby bringing about the de-energization 10 of the line relay 204. A short interval after the retraction of the armature 231, the slow acting relay 205 is de-energized to complete a circuit for the release magnet over a path which may be traced from ground by way of armature 231 15 and its back contact, armature 233 and its back contact, armature 223 and its back contact, off-normal spring 257 and its working contact, back contact and armature 271 and release magnet 211 to battery. The release magnet 211 is energized 20 to restore the switch wipers 216 to 219 inclusive, to their normal position in the usual manner. The de-energization of the slow acting relay 205 also disconnects ground from the release trunk conductor 192, which has established a holding 25 circuit for the selector switch S and the line switch RS. In the selector switch S the switching relay 128 is de-energized to complete a circuit for the release magnet 135 over a path which extends from ground by way of armature 150 and 30 its back contact, back contact and armature 149, armature 152 and its back contact, working contact of off-normal spring 157 and said spring, switch wiper 160 of timing switch RS-1 first bank contact, and release magnet 135 to battery. 35 The release magnet 135 is energized to restore the switch wipers 136 to 138 to normal. The disconnection of ground from the release trunk conductor also brings about the de-energization of the switching relay 108 of the rotary line switch 40 RS, which upon de-energizing connects the calling line to the line relay 108 so as to prepare the rotary line switch for another call.

It will now be assumed that the line of the sub-station T-1 when called by the subscriber at 45 sub-station T was idle. In this instance when the switch wipers 216 to 219 inclusive, of the connector C are brought into engagement with the bank contacts 292, 296, 294 and 298, there will be no ground potential upon the test contact 295 50 and no circuit will be completed for the busy test relay 208. Now a short interval after the calling device CD at the calling sub-station T is restored to normal, the slow acting relay 209 will be de-energized to complete a circuit for the 55 switching relay 210 over a path which extends from ground by way of front contact and armature 214, armature 240 and its back contact, lower winding of relay 210 back contact and armature 243, test wiper 217, bank contact 296, conductor 305, relay 346, back contact and armature 350, and motor magnet 344 to battery. The switching relay 210 is energized over this circuit and operates to establish a locking circuit for itself at armature 253 to open a point in the 65 locking circuit of the busy test relay 208 at armature 252 to open a point in the circuit of the rotary magnet at armature 254 to apply ground to the test wiper 217 at armature 255 and to complete the ringing circuit at armatures 258, 251 70 and 256. The application of ground to the busy test wiper applies a full ground potential to the conductor 306 to busy the called line.

The switching relay 346 in the line switch RS-3 associated with the called sub-station T-1 75

is energized, but by reason of an interlocking device controlled by the armature of the line relay 345, the armatures 347, 348, 349 and 351 are only partially operated sufficient to disengage their back contacts but not to engage their front contacts. In this manner the called line is cleared of attachments. A ringing circuit is now established which extends from ground by way of back contact and armature 239, front contact and armature 256, wiper 217, bank contact 298, conductor 307 over the line of the called telephone through its ringer, condenser, switch hook, springs of push button 236, over line conductor, conductor 302, bank contact 294, wiper 216, armature 250 and its front contact, armature 236 and its back contact, upper winding of ring cut-off relay 207 and thence to battery either through the ringing generator R or the armature 291 and its back contact. The relay 207 is not operated by the alternating current passing over this circuit. Ringing current is intermittently applied to the called line until the subscriber at sub-station T removes his receiver, whereupon there is a circuit for direct current over the line of the called telephone and the relay 207 is energized to establish a locking circuit for itself at armature 237. This locking circuit is established before any other armature or springs of the relay are operated. The relay 207 upon operating opens a point in its own energizing circuit at armature 236 at the front contact of this armature, completes a point in the talking circuit, completes a point in the circuit of a supervisor signal at armature 238, opens a point in the ringing circuit at armature 239 and at the front contact of this armature completes the talking circuit. The talking circuit extends to the called telephone over the heavy conductors shown in the drawings. The calling telephone is supplied with talking current through the windings of the line relay 204, while the called telephone is supplied with talking current through the windings of the relays 200 and 201 over a circuit which may be traced from ground through the lower winding of the marginal relay 201, lower winding of back bridge relay 200, front contact and armature 239, front contact and armature 256, wiper 217, bank contact 298, conductor 307, called telephone line, conductor 302, bank contact 294, wiper 216, armature 250 and its front contact, armature 236 and its front contact, upper winding of back bridge relay 200 and upper winding of marginal relay 201 to battery. The back bridge relay 200 on the marginal relay 201 are energized over this circuit. The relay 201 upon operating prepares a point in the circuit of the differential relay 203 at armature 224 and at armature 225 opens a point in the circuit of the upper winding of this relay. The relay 200 upon operating opens a point in the circuit of a supervisor signal at armature 228, and its back contact, and at the front contact of this armature establishes a further locking circuit for the switching relay 210, completes a circuit for the lower winding of the differential relay 203 at armature 221, and at armature 222 prepares a circuit for the upper winding of the differential relay. Another result of the operation of the relay 200 is that at armature 223 a point in the circuit of the release magnet is opened and at the front contact of this armature a point in the circuit of a supervisor signal is established. The circuit for the lower winding of the differential relay 203 may be traced from ground by way of front contact and armature 214, armature 221 and its

front contact, armature 224 and its front contact, and lower winding of differential relay 203 to battery. The differential relay 203 is energized over this circuit to establish a locking circuit for its lower winding at armature 229 to complete a circuit for the motor magnet 264 of the timing switch RS-2 at armature 230 and to reverse the connections of the line relay 204 with respect to the trunk conductors 197 and 198 at armatures 227 and 228, respectively. The reversal of the connections of the line relay as described bring about the operation of the timing switch RS-1, associated with the selector S as will be explained. The circuit for the motor magnet 264 may be traced from ground by way of front contact and armature 214, armature 230 and its front contact, the bank contact with which the switch wiper 275 is in engagement with when the switch RS-2 is in normal or initial position, switch wiper 275, back contact and armature 265, and motor magnet 264 to battery. The motor magnet 264 is operated over this circuit to advance the switch wipers 273 to 276, inclusive, of the timing switch RS-2 into engagement with the second set of bank contacts. The operation of the timing switch RS-2 is thus initiated by the response of the called party at sub-station T-1, but its operation has no particular function at the present time and the description of its operation will be left until it does function, which occurs when the charge is to be assessed against the called line.

It is to be noted at this time that when the switch wipers 216 to 219 inclusive, of the connector switch C are brought into engagement with the bank contacts associated with the called line of the sub-station T-1, there was a circuit completed for the high resistance relay 202, if this call was made at certain periods of the day. This depends upon the operation of the clock switch M-1, which may be of any usual or well known type. It will be seen that the wiper 261 of the switch M-1 is adapted to connect battery to the common conductor 246, if the common conductor is tapped into certain bank contacts representing the hours of the day. Consequently, the periods during which battery is applied to this conductor may be regulated. The connection of battery to this conductor determines whether or not the called party may reverse the charge by the use of instrumentalities as his sub-station. If battery is not connected to this conductor, he cannot alter the charge being assessed to the calling line. This may be desirable at certain periods of the day, as warranted by traffic conditions.

It will be assumed in the present instance, however, that at the time the switch wipers of the connector were brought into engagement with the bank contacts of the called line battery was connected by the clock switch M-1 to the common conductor 246. In this instance there is a circuit completed for the relay 202, which extends from battery through the winding of the relay 202, front contact and armature 245, switch wiper 216, bank contact 292, conductor 300, meter 352 of the called line, associated with switch RS-3 to ground. The meter 352 is not operated over this circuit by reason of the high resistance of the relay 202. However, this relay is energized to prepare a circuit for the upper winding of the differential relay 203 at armature 226. This prepares a circuit by which the called line may reverse the charges.

Referring now to the description of the opera-

tion by which a time charge is assessed to the meter on the calling line, it will be recalled that the response of the called party brought about a reversal of battery over the conductors 197 and 198. This reversal of battery brings the current flow in the lower lining of the electro polarized relay 127 in the same direction as the current flow in its upper winding and this relay is energized to complete a circuit for the relay 126 at armature 143 and to complete a circuit at armature 145 for the motor magnet of the timing switch RS-1. The circuit for energizing the motor magnet 158 extends from ground upon the release trunk by way of armature 145 and its front contact, bank contact with which the switch wiper 161 is in engagement in normal position of the switch wipers, said wiper, back contact and armature 163 and motor magnet 158 to battery. The slow acting relay 126 upon operating prepares a circuit at armature 142 for the relay 125.

The motor magnet 158 is operated over the above traced circuit to advance the switch wipers 159 to 162 of the timing switch RS-1 associated with the selector S, one step into engagement with the second set of bank contacts. The movement of the switch wiper 161 opens the previously traced circuit for the motor magnet 158. However, the operation of the switch wipers and more particularly the switch wiper 162 into engagement with the second set of bank contacts prepares a circuit for the operation of the motor magnet 158, which includes the interrupter or commutator 173 mounted upon the shaft 174 and connected to ground. As explained before, the shaft 174 is being constantly rotated at a pre-determined speed. All bank contacts, except the last four and the first one of the rotary switch RS-1, are multiple together and connected to the armature 171 of the relay 170. Consequently, as the shaft 174 is rotated, ground is periodically connected to the winding of the motor magnet 158, which is periodically operated to advance the switch wipers 159 to 162 over the bank contacts. The advancement of the switch wipers of the rotary switch RS-1 continues as a result of the impulsive circuit to motor magnet 158 described, until the switch wipers are brought into engagement with the fourth from the last set of bank contacts, whereupon the impulsive circuit for the motor magnet 158 is transferred to the commutator 178 mounted upon the shaft 181. This shaft is moving at a slower speed than shaft 174 and consequently the switch wipers are not advanced so rapidly. Furthermore, during one revolution of the commutator 178, only one circuit is completed for the motor magnet 158, which further delays the advancement. When the switch wipers are brought into engagement with the third from the last set of bank contacts there will be a tone connected to the talking circuit over a path which extends from the tone machine by way of the conductor 191, commutator 176, condenser 182, bank contact with which the switch wiper 160 is in engagement, armature 166 and its back contact, condenser 167, to the talking circuit. The tone machine connected to the conductor 191 gives a distinctive tone slightly in advance of the metering charge to apprise the calling party that a charge is about to be made. When the switch wipers of the switch RS-1 are brought into engagement with the second from the last set of bank contacts there is a circuit completed for the relay 170 over a path which may be traced

from the metering battery B through the commutator 177 when in the proper position, wiper 159, second from the last bank contact, and upper winding of relay 170 to ground. The relay 170 is energized over this circuit to establish a locking circuit through its lower winding to ground upon the release trunk conductor at armature 180 and to disconnect the bank contacts that control the periodic operation of the motor magnet 158 of the rotary switch RS-1 from the commutator 173 and connect them to the commutator 172. The purpose of this operation is for the reason that the usual practice in assessing telephone charges is to assess an initial charge for an interval of time; thereafter to assess a charge for every minute or a shorter interval of time. By reason of the number of segments on the commutator 172 the switch wipers are stepped more rapidly to accomplish the difference in charges. The operation of the switch wiper 160 into engagement with the second from the last bank contacts connects the tone from the tone machine connected to the conductor 190 to the talking circuit whereby the calling subscriber is apprised that his meter is being operated to assess the charge. The motor magnet 158 continues to be operated periodically by reason of the ground connection through the commutator 178. The purpose of switching the control of the motor magnet during the last four steps of the metering switch RS-1 is to provide for uniform operation of the switch over the last segments. This permits the tones to be applied to the talking circuit for a uniform interval, irrespective of the speed of operation of the motor shaft 174.

It should be mentioned at this time that the speed of the motor shaft 174 may vary in accordance with the time of day, or in accordance with traffic conditions in the exchange so as to provide a greater charge in the event that the call is made during a peak load or during ordinary load.

When the switch wipers are stepped into engagement with the last set of bank contacts there is a metering circuit completed for energizing the meter 107 of the calling line. This circuit may be traced from the metering battery through the commutator 177, wiper 159, last bank contact, back contact and armature 140, bank contact 121, wiper 110, front contact and armature 115 and meter 107 to ground. The meter 107 is operated over this circuit to assess a charge against the calling line.

It will be understood that during the operation of the rotary switch RS-1, which has been initiated by the removal of the receiver at the called telephone the subscribers may carry on their conversation. The operation of the rotary switch RS-1 continues past the last set of bank contacts and the switch wipers 159 to 162 in their continued rotation are brought into engagement with their normal set of bank contacts. The operation of the switch RS-1 continues in identically the same manner as described, with the same results. Its operation during this second movement is faster than the first by reason of the operation of the relay 170 previously described.

In the usual course of events the operation of the timing switch RS-1 will continue until the calling subscriber replaces his receiver upon the switch hook at the end of the conversation and the meter 107 will be assessed in accordance with the time the telephone has been used and the

rate or rates prevailing during that period of time.

Under these conditions when the calling subscriber replaces his receiver, the circuit of the line relay in the connector 204 will be opened and this relay will be de-energized to open the circuit of the relay 205. A short interval of time thereafter the relay 205 is de-energized to remove ground from the release trunk conductor 196, whereby the switching relays 128 and the selector S and 108 in the line switch RS are de-energized. The de-energization of the relay 128 in the selector switch S brings about its release in the same manner as has already been described. In order to restore the wipers of the rotary switch RS-1 to normal position, when the relay 128 is de-energized, there is a circuit completed which extends from ground by way of armature 151 and its back contact, armature 164 and its back contact, bank contacts engaged by the switch wiper 161, back contact and armature 163 and motor magnet 158 to battery. This circuit serves to bring about the continued operation of the motor magnet 158 to advance the switch wipers into their normal position. The removal of ground from the release conductor also opens the locking circuit of the relay 179 and this relay is de-energized to restore a connection of the commutator 173 and its associated bank contacts.

The rotary switch RS is restored to normal in the same manner as previously described. In the connector switch C, if the called subscriber has not yet placed his receiver upon the switch hook, the circuit of the release magnet is maintained open and the connector is not released until the called subscriber hangs up his receiver. The rotary switch RS-2 is, however, restored to normal by the connection of ground to the bank contacts accessible to wiper 215, which brings about the continued operation of the motor magnet 264 in an obvious manner. The switch wipers 273 to 276, inclusive, are rotated to their normal position. When the called subscriber hangs up there is a release circuit established for bringing about the release of the connector C, which may be traced from ground by way of armature 231 and its back contact, armature 233 and its back contact, armature 223 and its back contact, off-normal spring 257 and its working contact, back contact and armature 271, and release magnet 211 to battery. The release magnet 211 is operated over this circuit to restore switch wipers of the connector switch to normal. The de-energization of the relay 200 responsive to the called subscriber replacing his receiver brings about the de-energization of the relays 207 and 210 and these relays retract their armatures to restore their respective circuits to normal.

Attention is directed to the fact that the selector switch S cannot be restored to normal until the rotary switch RS-1 is in normal position, though if the calling subscriber replaces his receiver upon the switch hook immediately after the called party answers and before a charge is made or responsive to his initial tone indicating a charge about to be made, the meter 107 will not be operated. This provision is made so that there will be no charge in the event a wrong number is obtained.

Attention is also directed to the fact that if the called subscriber does not immediately replace his receiver and the connector remains in operated position, ground is connected by way

of armature 223 and its front contact to the supervisory signal to indicate this fact, and an attendant can remedy the situation, if the condition persists.

It will now be assumed that during the progress of the call between the sub-stations T and T-1, as before described, that the called party desired to have the charge assessed against his line and not against the calling line.

Under these conditions, the circuit it will be assumed, is established as before, employing the line switch RS, selector S and connector C. It will be recalled that immediately upon the called subscriber at station T-1 removing his receiver the relays 200, 201 and 203 in the connector and the relays 126 and 127 in the selector were operated. As a result of these operations the rotary switches RS-1 and RS-2 associated with the selector S and connector C respectively, begin to operate in the same manner as described. The charge will be against the calling line until the subscriber at sub-station T-1 depresses his push button 336. When this occurs the shunt around the resistor 335 included in the line circuit is removed and the marginal relay 201 in the connector C is de-energized. By the de-energization of this relay a point in the circuit of the lower winding of the differential relay 203 is opened and a circuit is provided for the upper winding of the differential relay 203, provided of course the metering switch or time switch M-1 is in the proper position with the relay 202 energized. The circuit for the upper winding of the differential relay 203 extends from ground by way of front contact and armature 214, front contact and armature 229, armature 222 and its front contact, armature 225 and its back contact, armature 226 and its front contact and upper winding of differential relay 203 to battery. The relay 203 is de-energized since current in both windings oppose. As a result of the de-energization of the relay 203, the connections of the line relay 204 with respect to the trunk conductors 197 and 198, is restored to normal. Another result of the operation of the relay 203 is that an armature 229 in the circuit of both windings is opened. By the engagement of armature 230 of the relay 203 with its back contact, there is a circuit completed extending from ground on release trunk conductor 196, armature 230 and its back contact, back contact and armature 271 and relay 263 to battery. The relay 263 is energized to establish a locking circuit for itself at armature 270 to open a point in the circuit of the release magnet at armature 271 to prepare a metering circuit at armature 269 and to prepare a circuit at armature 268 for applying tone to the talking circuit.

As a result of the reversal of connections of the line relay 204 of the connector as described by the de-energization of the differential relay 203, the current flow through the lower winding of the electro polarized relay 127 is again changed and opposes the current flow in its upper winding. As a result of this operation, the armatures 143 and 145 of this relay are retracted. The operation of the armature 143 serves to complete a circuit for the relay 125 over a path extending from ground on the release trunk conductor, armature 143 and its back contact, armature 142 and its front contact, and relay 125 to battery. Relay 125 is energized over this circuit to establish a locking circuit for itself at armature 139 to open a point in the circuit ex-

tending to the meter of the calling telephone at armature 149 to prepare a point in the release circuit at armature 141 and to open the connection by which tone through the switch RS-1 is applied to the talking circuit at armature 166. As a result of the energization of relay 125 the continued operation of the rotary switch RS-1 is ineffective.

When the called subscriber releases the push button 336, a shunt is again replaced around the resistor 335 and the relay 201 in the connector is again operatively energized to attract its armatures 224, 225 and 277. The operation of its armature 225 opens a point in the circuit of the upper winding of the differential relay 203, while the operation of the armature 277 opens a point in the circuit of the relay 263. The operation of the armature 224 serves to again establish a circuit for the lower winding of the differential relay 203, whereby the connections of the line relay 204 with respect to the talking conductors 197 and 198 is again reversed. The reversal of these connections again brings about the energization of the electro polarized relay 127 in the connector S, but its operation has no particular function at this time.

It will be recalled that when the relay 203 was originally energized, the motor magnet 264 of the rotary switch RS-2 was operated and that the wipers of the rotary switch RS-2 were advanced one step into engagement with the second set of bank contacts. By this advancement the original circuit for the motor magnet is broken at the wiper 275 and another circuit was established for this magnet, which extends by way of the wiper 276, second set of bank contacts, armature 267 and its back contact and commutator 285 on the shaft 289 to ground. The motor magnet is periodically operated by the operation of the commutator 285 advancing the switch wiper step by step at a definite rate of speed. When the switch wipers are brought into engagement with the fourth from the last set of bank contacts, the circuit for operating the motor magnet above described is switched to the commutator 287 on the shaft 288, which moves uniformly. When the switch wipers are advanced into engagement with the third from the last set of bank contacts, if the subscriber of the called sub-station has depressed his push button at this time to bring about a reversal of charges, a tone from the tone machine 280 is applied to the talking circuit over a path that may be traced from the tone machine, commutator 283, third from the last set of bank contacts, wiper 274, front contact and armature 268, condenser and thence to the talking circuit. This tone apprises the subscribers that a charge is about to be made. The tone may be of different pitch than the tone connected either to the conductors 190 or 191 associated with the selectors, and apprises the subscribers the charge is to be made against the called telephone. When the switch wipers are advanced into engagement with the second from the last set of bank contacts, the tone from the tone machine 281 is connected to the talking circuit and will apprise the subscribers that a charge is being made against the called telephone. As before described, the shaft 288 of the metering equipment M-2 may be driven at varying rates, depending upon the time or traffic conditions to make a charge in accordance with the amount of traffic in the exchange or in accordance with the time of day.

75 When the switch wiper 273 is brought into en-

gagement with the last set of bank contacts there is a metering circuit completed, which extends from the metering battery B-1, commutator 284, wiper 273, last bank contact, front contact and armature 269, front contact and armature 278, front contact and armature 245, wiper 214, bank contact 292, conductor 300, and meter 352 associated with the line switch of the called telephone to ground. The meter 352 is operated to assess the charge against the called telephone.

When the switch wiper 273 was in engagement with the second from the last set of bank contacts there was a circuit completed for the upper winding of the relay 262. The relay 262 is energized to establish a locking circuit for itself at armature 266, which extends to release trunk ground, and connects the impulsing circuit through the commutator 286 to provide that faster operation of the timing switch RS-2 during its second operation may be had. So long as the subscribers 10 at sub-stations T and T-1 are in communication, the time charge will be assessed against the called telephone in accordance with the traffic conditions.

When the conversation is finished the subscribers will replace their receivers upon their respective switch hooks and the various switches employed in the connection will be restored to normal in the manner already described.

Attention is directed to the fact at this time 30 that in the event the called subscriber hangs up and the calling subscriber maintains the connection, the de-energization of the relay 200 responsive to the replacement of the switch hook at the called telephone opens the metering circuit 35 at armature 278 so that the calling subscriber cannot make an unfair charge against the called subscriber.

When the conversation is terminated the subscribers will replace their receivers upon their 40 respective switch hooks. As a result of the replacement of the receiver at the calling station, the line relay 204 in the connector C will be de-energized and the slow acting relay 205 will be de-energized a short time thereafter to remove 45 ground from the release trunk conductor 196, thereby bringing about the release of the line switch RS, selector S, and the restoration to normal of the timing switch RS-1, individual to the selector in a manner similar to that already described. The de-energization of the relay 205 also causes the timing switch RS-2 to be restored to normal by applying ground to the bank contacts accessible to the wiper 275. This ground connection causes the motor magnet 264 to operate to rotate the switch wipers 273 to 276 inclusive, to their normal position. When the called subscriber hangs up, the circuit for the release magnet 211 is completed and the connector switch C is released in a manner similar to 50 that already described.

From the foregoing it will be seen that there is a time charge made against the calling line upon the response of the called line under the control of a rotary switch, such as RS-1 individual to 65 the selector used. It is desirable that the rotary switches such as RS-1 be rotated relatively rapidly under the control of the impulsing device 173, somewhat more rapidly under the control of the impulsing device 172. This arrangement 70 should be so that the initial rotation of the rotary switch RS-1 will occur in approximately twenty seconds, though this period may be varied as desired, and that the second rotation will occur at a relatively faster speed. This provision should be 75

made in order that the calling subscriber cannot hold a conversation with the called subscriber for any particular period of time for the charges made. The meters such as 107 and 352 can be 5 regulated to make the proper charge for the usual number of operations.

In a like manner the switches such as RS-2 associated with the connector should be arranged to rotate at substantially the same speed as the 10 timing switches RS-1.

It will be seen that the charges made to the called subscriber's line at his option are in accordance with the time that the telephone talking circuit is in use. Attention is also directed to the 15 fact that means are provided for indicating to the subscribers which line the charge is being assessed against and also when the charge is made.

The telephone sub-station T-2 is somewhat 20 modified so that instead of the push button such as 337 removing the short circuit about a resistor, the depression of the push button grounds one side of the line. This grounding may be employed to operate a relay such as 201 in the 25 connector of the differential type instead of a marginal relay in an obvious manner. Under these conditions the results will be identical with those described.

In a metering system such as has been described 30 it is desirable that certain telephone lines such as those belonging to the telephone company be arranged for a free charge, so that no charge will be made to the calling party in the event connection is made with any of these lines. 35 In order to accomplish this result the line extending to a free telephone is provided with the relay equipment associated with the line switch, such as RS-4. The bank contact which ordinarily would be connected to the meter in the 40 connectors such as 293 is connected through a resistor to ground.

A short description of the matter in which a 45 call is made to a line of this character and the functioning of equipment under these conditions, and particularly the difference between this kind of a call and a regular call will now be described. In establishing the connection from the calling telephone T to the called telephone T-3 of the free class, line switch RS of the calling line and a selector such as S, and a connector such as C, will be operated in identically the same manner 50 as before described to establish the connection. It will be assumed that the selector switch S and the connector C are the ones employed to establish the connection. Connector switch C will be 55 operated so as to bring its wipers 216 to 219 inclusive, into engagement with the bank contacts 293, 297 and 295 and 299, respectively. The bell at the sub-station T-3 will be operated periodically to summon the subscriber thereto. When 60 the party at the telephone T-3 removes his receiver from the switch hook, the ring cut-off relay 207 is energized to establish a locking circuit for itself at armature 237 and connect the called line to battery through the back bridge relay 200 and the marginal relay 201. Both these relays are 65 operated with the same results as before. The differential relay 203 is also energized to reverse the connections of the line relay 204 with respect 70 to the trunk conductors 197 and 198. It will be seen that the relay 319 is included in the line circuit of the called telephone in parallel with a non-inductive resistance so as to provide a clear path for voice currents, and partially to short 75 circuit the relay 319 when ringing current is ap-

plied. When relay 319 is adjusted not to respond to ringing current, however, the relay 319 is energized in series with the relays 200 and 201 of the connector. The relay 319 upon operating completes a circuit for the slow to operate relay 318, and the relay 318 is made slow to operate to give the relays 200 and 201, as well as the relay 203, time to operate before this relay is energized. The operation of the relay 318 serves to complete a circuit for the relay 317 at armature 333 and to 10 open the short circuit around the resistor 336 at the armature 335. The removing of the short circuit around the resistor 336 includes this resistor in the circuit and permits the marginal relay 201 in the connector C to de-energize to 15 retract its armatures. The relay 317 upon energizing, opens a point in the circuit of the relay 318 at armature 331 and completes a locking circuit for itself at armature 332 to ground upon the release trunk conductor 306. The relay 318 20 is de-energized after an interval of time to open the original energizing circuit of the relay 317 and to again short circuit the resistor 336.

In the connector switch C the relay 201 upon de-energizing, completes a circuit for the upper 25 winding of the differential relay 203. The differential relay 203 retracts its armatures again to reverse the connections of the line relay 204 with respect to the trunk conductors 197 and 198, thereby bringing about the energization of the 30 relay 125 in the selector switch S. The operation of this relay renders the functioning of the timing switch RS-1 individual to the selector ineffective, it being remembered that this switch was started by the operation of the electro polarized relay 121 responsive to the first reversal of current over the conductors. The operation of the differential relay 203 brings about the energization of the relay 263 and brings the timing switch RS-2 into play. However, since the 35 metering wiper 214 extends to ground through a resistor by way of the bank contact 293, the metering switch RS-2 is ineffective to assess any charge, there being no meter connected with the telephone T-3, as it is an official or free telephone. In this manner no charge is made to the 40 calling subscriber when he calls a free telephone number.

When the conversation is terminated the connection is released in a manner similar to that 45 already described.

It is possible in a telephone system of this character that some of the lines other than company lines may not be provided with meters, but be operating on a flat rate basis. In this instance there will be no meter connected to this 50 class of lines. The meter bank contacts 293 in the various connectors having access to this class of lines are simply left open. The purpose of leaving these bank contacts open is to prevent the called party exercising any control whatsoever over the metering charge. It will be seen that if the bank contact such as 293 is left open there is no circuit that may be completed for the relay 202, which controls the de-energization of the differential relay 203. Consequently, a called party having such service could not by any manipulation or appliance on his telephone line cause the disconnection of the metering charge to the calling party, which 55 he might do were it not for this provision.

From the foregoing it will be obvious also that a certain amount of the charge may be assessed against the calling line and thereafter further charge may be made against the called 60 65 70 75 75

line, depending upon the time at which the called party exercises his reverse control.

The clock switch M-1 provides means by which, during certain hours of the day, a certain group of lines or all lines in the exchange may not have this reverse service.

Having described certain specific embodiments of my invention, I am aware that many changes, departures and deviations may be made therefrom, without departing from the spirit and scope thereof, as indicated in the appended claims:

I claim:

1. In an automatic telephone system, the combination of telephone lines, a metering device associated with each line, means including automatic switches for establishing a connection between a calling and called one of said lines, and means for operating the metering device on 15 either the calling or called line after the establishment of said connection, starting of the operation of the meter on the called line being optionally controlled over the called line at any time after the connection is established.

2. In an automatic telephone system, the combination of telephone lines, a metering device associated with each line, means including automatic switches for establishing a connection between a calling and called one of said lines, and means controlled from one of the telephone lines after the connection is established for operating the meter on the calling or called line over a part of said connection extending from the corresponding calling or called end of the connection, the starting of the operation of the called meter being optionally controlled by the called subscriber at any time after the connection is established.

3. In an automatic telephone system, the combination of telephone lines, a metering device associated with each line, means including automatic switches for establishing a connection between a calling and called one of said lines, and means optionally controlled from the called telephone line at any time after the connection is established for starting and continuing the operation of the meter on the called line.

4. In an automatic telephone system, the combination of telephone lines, a metering device associated with each line, means including automatic switches for establishing a connection between a calling and called one of said lines, means normally operative to start the calling line meter responsive to the connection, and means for starting and continuing the operation of the meter on the called line under the control of the subscriber therat as a result of the establishment of the connection.

5. In an automatic telephone system, the combination of telephone lines, a metering device associated with each line, means including automatic switches for establishing a connection between a calling and called one of said lines, and means controlled at the option of the called telephone line at any time after the connection is established for initiating and continuing the periodic operation of the meter on the called line as a result of the establishment of the connection.

6. In an automatic telephone system, the combination of telephone lines, a metering device associated with each line, means including automatic switches for establishing a connection between a calling and called one of said lines, means for operating the meter on the calling line during an initial portion of the time that the connection is established, and means for operating the meter on the called line during another portion of the time that the connection is maintained.

7. In an automatic telephone system, the combination of telephone lines, a metering device associated with each line, means including automatic switches for establishing a connection between a calling and called one of said lines, means normally operative responsive to the connection for operating the meter associated with the calling line during an initial portion of the time that said connection is established, and means for operating the meter on the called line during another portion of the time that the connection is maintained.

8. In an automatic telephone system, the combination of telephone lines, a metering device associated with each line, means including automatic switches for establishing a connection between a calling and called one of said lines, means normally operative responsive to the connection for operating the meter associated with the calling line during an initial portion of the time that said connection is established, and means for operating the meter on the called line during another portion of the time that the connection is maintained; said latter means being controlled from the called line.

9. In an automatic telephone system, the combination of telephone lines, a metering device associated with each line, means including automatic switches for establishing a connection between a calling and called one of said lines, means for operating the meter on the calling line as a result of the establishment of the connection and removal of the called receiver and means for signalling the subscriber at the calling station to indicate the operation of said meter.

10. In an automatic telephone system, the combination of telephone lines, a metering device associated with each line, means including automatic switches for establishing a connection between a calling and called one of said lines, means for operating the meter on either the calling or called line, and means for signalling the subscribers on said lines to indicate against which line the charge is made.

11. In an automatic telephone system, the combination of telephone lines, a metering device associated with each line, means including automatic switches for establishing a connection between a calling and called one of said lines, means normally operative to start the calling line meter responsive to the connection, means controlled by the called subscriber for initiating and continuing the operation of the meter associated with the called line periodically while said connection is maintained, and means for varying the periods of time between said meter operations.

12. In an automatic telephone system, the combination of telephone lines, a metering device associated with each line, means including automatic switches for establishing a connection between a calling and called one of said lines, means normally operative to start the calling line meter responsive to the connection, means controlled by the called subscriber for initiating and continuing the operation of the meter associated with the called line periodically while said connection is maintained, and means for varying the periods of time between said meter op-

erations, depending upon the time of day during which the connection is established.

13. In an automatic telephone system, the combination of telephone lines, a metering device associated with each line, means including automatic switches for establishing a connection between a calling and called one of said lines, means normally operative to start the calling line meter responsive to the connection, means controlled by the called subscriber for initiating and continuing the operation of the meter associated with the called line periodically while said connection is maintained, and means for varying the periods of time between said meter operations, depending upon the traffic load of exchange.

14. In an automatic telephone system, telephone lines, a metering device individual to certain of said lines, means including automatic switches for establishing a connection between a calling and called one of said lines, and means operative if there is a meter associated with each of the connected lines for first operating the calling meter and then the called meter at the option of the called subscriber.

15. In an automatic telephone system, telephone lines, a meter individual to certain of said lines, automatic switches including first selectors and connectors for establishing connections between a calling and called one of said lines, a timing switch associated with each first selector, a timing switch associated with each connector, means under the control of the timing switch at the first selector for operating the meter associated with the calling line, means under the control of the timing switch at the connector for operating the meter associated with the called line, and means under the control of one of the lines for determining which timing switch will be effective to operate the associated meter.

16. In an automatic telephone system, the combination of telephone lines, a metering device associated with each line, automatic switches including a first selector and connector for establishing a connection between a calling and called one of said lines, a timing switch associated with said first selector, means for initiating the operation of said timing switch as a result of the response of the subscriber on the called line, means under control of said timing switch for operating the meter associated with the calling line, and means controlled by the called subscriber to transfer the charge from the calling meter to the called meter.

17. In an automatic telephone system, the combination of telephone lines, a metering device associated with each line, automatic switches including a first selector and connector for establishing a connection between a calling and called one of said lines, means normally effective to operate the calling line meter responsive to the connection, a timing switch associated with said connector, means for initiating the operation of said timing switch as a result of the response of the subscriber on the called line, and means under the control of the called subscriber for rendering the calling line meter operating means ineffective and for causing said timing switch to become effective to actuate the meter associated with the called line.

18. In an automatic telephone system, telephone lines, a meter individual to certain of said lines, automatic switches including first selectors and connectors for establishing connections between a calling and called one of said lines, a tim-

ing switch associated with each first selector, a timing switch associated with each connector, means under the control of the timing switch at the first selector for operating the meter associated with the calling line, means under the control of the timing switch at the connector for operating the meter associated with the called line, and means for initiating the operation of both timing switches as a result of the response of the subscriber on the called line.

19. In an automatic telephone system, a combination of telephone lines, a metering device associated with each line, automatic switches including a first selector and connector for establishing a connection between a calling and called one of said lines, a timing switch associated with first selector, and a timing switch associated with the connector, means for initiating the operation of said timing switches as a result of the response of a subscriber on a called line, means controlled from the called line for rendering the timing switch associated with the first selector to become effective to actuate the meter associated with the calling line, and means controlled from the called line for causing the timing switch associated with said connector to become effective to actuate the meter associated with the called line.

20. In an automatic telephone system, the combination of telephone lines, a metering device associated with each line, automatic switches for connecting a calling and called one of said lines, means for operating the metering device on the calling and then the called line after said connection is established, and means controlled over the called telephone line for determining whether the called meter is to be operated or only the calling meter.

21. In an automatic telephone system, the combination of telephone lines, a metering device associated with each line, automatic switches for connecting a calling and called one of said lines, means for operating the metering device on the calling and then the called line after said connection is established, and means controlled over the called line for effecting said consecutive operation of both meters.

22. In an automatic telephone system, the combination of telephone lines, a metering device associated with each line, automatic switches for connecting a calling and called one of said lines, means for operating the metering device on the calling line after said connection is established, and means controlled over the called line for continuing the operation of the calling meter or effecting the operation of the called meter and stopping the continued operation of the calling line meter.

23. In an automatic telephone system, telephone lines, a metering device individual to said lines, means including automatic switches for establishing connections between calling and called lines, and means made operative if there is a meter associated with each of two connected lines for operating the calling meter and then the called meter for the duration of the connection at the option of the called subscriber.

24. In an automatic telephone system, telephone lines, a metering device individual to each line, automatic switches for establishing connections between calling and called lines, means for operating a calling line meter responsive to the removal of the receiver of the called line, and means for thereafter transferring the registration of the call from the calling meter to the

called line meter at the option of the called subscriber.

25. In an automatic telephone system, telephone lines, a metering device individual to each line, automatic switches for establishing connections between calling and called lines, means for operating a calling line meter responsive to the removal of the receiver of the called line, and means for transferring the registration of the call 10 from the calling meter to the called line meter at the option of the called subscriber at any time during the maintenance of the connection.

26. In an automatic telephone system, telephone lines, a metering device individual to each line, automatic switches for establishing a connection between a calling and a called line, a timer for operating the calling line meter, a timer for operating the called line meter, means for operating the calling line meter by its associated timer responsive to the removal of the receiver of the called line, and means optional with the called subscriber to operate the called line meter by its timer to start the registration of the 15

call and stop the calling meter for the remainder of the call.

27. In an automatic telephone system, the combination of telephone lines, a metering device associated with each line, means including automatic switches for establishing a connection between a calling and called one of said lines, means for operating the meter device on the calling line as a result of the establishment of the connection and removal of the called receiver, means for signalling the subscriber at the calling station an interval of time before the meter is so operated and for sending a second signal to the calling subscriber to indicate that the meter is being operated. 10
